UNITED STATES PATENT OFFICE

WILLIAM A. HANNUM, OF GRAND LAKE, COLORADO

AUTOMATIC DRAFT CONTROLLING DEVICE

Application filed October 23, 1930. Serial No. 490,739.

The present invention relates to draft control devices and more particularly to means for controlling the entrance of air into furnaces, stoves, fire boxes, boilers or the like.

An object of this invention is to provide an automatically operated air controlling device which may be secured to a conventional furnace or boiler without interfering with the present parts of the furnace or boiler and which will control the quantity of fresh air admitted to the furnace from the exterior of the building regardless of the pressure of the atmosphere of air inside of the building.

Another object of this invention is to provide a device of this kind with a balanced valve or damper which is automatically controlled by the amount of suction and pressure exerted from the exterior of the building.

The above and various other objects and advantages of this invention will in part be described in and in part be understood from the following detailed description of the present preferred embodiment, the same being illustrated in the accompanying drawings, wherein:

Figure 1 is a horizontal sectional view taken substantially through the center of a device constructed according to the preferred embodiment of this invention;

Figure 2 is a detail side elevation of the device;

Figure 3 is a sectional view taken on the line 3—3 of Figure 1;

Figure 4 is a sectional view taken on the line 4—4 of Figure 1;

Figure 5 is a vertical sectional view taken substantially on the line 5—5 of Figure 4;

Figure 6 is an enlarged fragmentary sectional view showing in detail the method of supporting the air controlling member, and

Figure 7 is a sectional view showing a modification of the device.

Referring to the drawings wherein like numerals of reference designate corresponding parts throughout the several views, the numeral 10 designates generally a furnace or heating member which is provided at the desired point with an ash door 13 which is hingedly secured to the furnace or heating unit 10 and engages against an outstanding

box or flange 11. In the heating units at present available, the air used in the combustion of the fuel is drawn from the interior of the building and this use of the air within the building causes a reduction of the air pressure within the building and the air outside of the building seeps into the interior through cracks or the like so as to equalize the pressure within the interior and exterior of the building.

While numerous devices have been devised for taking the air from the exterior of the building and passing it about the heating shell or unit, these devices have for their main object the provision of fresh air which is drawn about the heating shell for use within the rooms or interior of the building, but this air is not used for combustion purposes or passed into the fire box of the heating unit.

In order, therefore, to provide adequate means for passing fresh air into the fire box, I have provided an air conduit 12 which is in communication at one end with the atmosphere outside of the building. The other or inner end of the conduit 12 has secured thereto a heat controlling unit generally designated as 14, the air controlling unit 14 comprising a boxing of any desired configuration which is provided at the outer end thereof with a partition or wall 15, the wall 15 having a pair of openings 16 therethrough, one of the openings 16 and 16' being positioned below the center of the partition 15 and the other opening being above the center and oppositely from the vertical center to the lower opening thereby providing a pair of staggered openings from the conduit 12. The controlling unit 14 is also provided with an inner wall 17 which is also provided with upper and lower staggered openings 18 and 18' therethrough which are positioned oppositely from the openings 16 in the outer wall 15.

A balanced damper 19 is pivotally mounted on a pair of adjustable trunnions 20 which are secured to the inner and outer wall members 17 and 15, respectively, and extend into the body of the damper 19 so as to swingably support the damper within the unit 14. The opposite ends of the damper 19 are pref-

- erably beveled, as at 21, and engage, when in closed position, against the inner surface of the walls of the air controlling unit 14 and a seat 22 is secured to the inner walls of the air controlling unit 14 and the damper 19 is adapted to also engage against the seats 22, the seats 22 cooperating with the inner surface of the unit so as to limit the swinging movement of the damper.
- 10 The dampers 19 are also provided with threaded pins 23 which are offset slightly from the axial center thereof and a threaded weight 24 is threadedly positioned on the bolts 23, the weights 24 being adapted to be adjusted so as to permit the damper 19 to be balanced within the unit 14. The damper 19 is provided with the balancing weights 24 on the opposite faces thereof so that a perfect balance may be secured by adjusting the 20 weights 24 inwardly or outwardly.

The air controlling unit 14 at the opposite sides thereof is preferably divided longitudinally so as to provide an upper portion 25 and a lower portion 26, the upper portion 25 being provided with a rabbet 27 which is engaged by a suitable rabbet in the lower portion 26. The unit 14 is also provided with a centrally disposed partition or wall 28 which extends longitudinally of the unit, the wall 28 being provided with an opening 29 extending substantially centrally therethrough for loosely receiving the damper plate 19 and so as to permit the damper 19 to have relative rocking movement within the unit 14.

The inner end of the unit 14 is provided with a pair of vertically disposed guides 30 on each side thereof in which is slidably mounted a vertically slideable damper or closure plate 31. The plate 31 cooperates with the inner partition 18 so as to provide a mixing chamber 32 within which the air passing inwardly through the air controlling unit 14 is adapted to be mixed and passed outwardly of the inner end of the unit 14. The extent of opening of the unit 14 is controlled by the vertical movement of the sliding plate 31.

The chamber 32 is provided at the upper surface thereof with an elliptical flange 33 upon which a closure plate 34 is positioned. This flange 33 provides an outlet from the air controlling unit 14 so as to permit the air within the air controlling unit 14 to be passed into the interior of the building and serves as a by-pass for the air.

In new furnaces, it is desirable to secure the air controlling unit 14 directly to the lower shell or base of the furnace or boiler as disclosed in Figure 7. However, where furnaces have already been installed and are not especially equipped to receive the air controlling unit as disclosed in Figure 7, the inner end of the air controlling unit 14 is provided with a hinged conduit 35 which is

hingedly secured to the unit 14 by means of conventional hinges 36 or the like.

The conduit 35 is preferably of tapering construction, being provided at the outer end thereof with an opening 37 and one face of the conduit 35 is preferably flat and coplanar with one wall of the air controlling unit 14. The flat side of the conduit 35 is adapted to engage against a packing plate 38 which engages against the outer edge of the flange 11 of the furnace 10.

Adjacent the inner end of the conduit 35 there is provided a flanged passage 39 which communicates with the passageway 40 in the furnace 10 which is conveniently used for removal of ashes from the base of the furnace. Through the use of the hinged conduit 35, it is possible to adapt the air controlling unit 14 to any furnace or boiler without in any way interfering with the present parts of the heating member, the conduit 35 being so hinged as to be swung away from the ash passage 40 as shown in dotted lines in Figure 1.

In the use of this device, the air controlling unit 14 is adapted to be secured to the conduit 12 which is in communication at the outer end thereof with the atmosphere exteriorly of the building and the closure door 31 is adapted to be moved upwardly of the unit 14 so as to provide the desired opening for the air to pass through the conduit 35 and into the furnace. When the vertically movable door 31 is pulled upwardly, the suction from the furnace 10 will swing the balancing damper 19 into open position and thereby draw the air through the passageways 16 and 18, the air passing inwardly of each face of the damper 19 so as to substantially cushion the rocking movement of the damper 19 within the unit 14.

When the wind pressure on the exterior of the building becomes excessive, the force of air passing through the opening 16 will have a tendency to close the damper 19 or to swing it into a position so as to limit the passage of air up to the capacity of the furnace 10 to receive the fresh air. Through the use of this device, the air used as combustion by the furnace will at all times be fresh air which is drawn from the exterior of the building and if desired, the fresh air may be passed about suitable preheating chambers before entering the furnace 10 so that when the air strikes the grates, it will be substantially heated air instead of cold air.

It will also be obvious from the foregoing that the outlet 33 may be connected to the shell of the furnace 10 so as to permit the fresh air to pass about the heated shell of the furnace and upwardly through the pipes in the conventional manner, thereby providing an air controlling unit which in addition to controlling the air entering the fire box of

the heating unit, the air controlling unit will also control the quantity of air passing into the preheating or air shell of the heating unit. In the event there should be any back pressure from the furnace, the back pressure would cause the damper 19 to swing immediately into closed position.

It is, of course, understood that various changes and modifications may be made in the details of construction and design of the above specifically described embodiment of this invention without departing from the spirit thereof, such changes and modifications being restricted only by the scope of the following claims.

I claim:—

1. An air controlling device of the character described, comprising a casing, an inner transverse wall mounted in the casing and having staggered openings therethrough, a longitudinally disposed wall mounted in the casing and engaging against said transverse wall, said longitudinally disposed wall having a longitudinally disposed opening therethrough, a rockable closure member mounted in the casing and engaging within said longitudinally disposed opening, said casing and said transverse wall having staggered openings therethrough whereby to permit the passage of air through the casing on opposite sides of said closure member and coactively cushioning the movement of said closure member, adjustable balancing means carried by said closure member for adjusting the balance thereof, and means for connecting the casing to a heating unit.

2. An air controlling means comprising a casing, an inner divided wall, said casing having a pair of openings in each end, one opening of each pair being on one side of the inner wall below the center thereof and the other opening being on the other side of the inner wall and above the center thereof, the openings in one end wall being opposite from the openings in the other wall, and a suction operated damper swingably mounted between the division of the inner wall.

3. An air controlling means comprising a casing, an inner wall including an upper and a lower wall member having their abutting edges spaced apart, a substantially balanced damper swingably mounted between said upper and lower wall members, said casing having openings in each end thereof so disposed as to swing the damper in open position by suction drawing air through the casing, and to close the damper by air pressure in excess of the suction.

4. An air controlling means comprising a casing, an inner wall mounted in substantially the longitudinal center of the casing, said inner wall having a longitudinally extending slot therethrough in substantially the center thereof, a damper swingably mounted in said slot, means for pivotally

mounting the damper, and balancing means carried by the damper, said casing having openings in each end thereof so disposed as to swing the damper in open position by suction drawing air through the casing and to close the damper by air pressure in excess of the suction.

5. An air controlling means comprising a casing, a vertical wall mounted within the casing and dividing the casing into two chambers, said inner wall having a longitudinally extending opening therethrough in substantially the center thereof, a damper mounted in said opening and having the opposite edges thereof normally engaged with the side walls of the casing, means for balancing the damper, said casing having openings in the end walls thereof communicating with the chambers, the openings in one end wall being reverse from the other end wall whereby to swing the damper into opened position by suction of air from one end and to automatically swing said damper into closed position upon increase in the air pressure on the opposite end in excess of the suction.

In testimony whereof I hereunto affix my signature.

WILLIAM A. HANNUM.
